Symestorff & Lechner

UNITED STATES PATENT OFFICE.

CARL S. REED, OF YONKERS, NEW YORK, ASSIGNOR TO INTERNATIONAL COMBUSTION ENGINEERING CORPORATION, OF NEW YORK, N. Y., A CORPORATION OF DELAWARE.

AIR PREHEATER.

Application filed December 3, 1925. Serial No. 72,889.

This invention relates to air preheaters, and is particularly useful in connection with waste gas air preheaters, such as are used in pulverized coal burning boiler installations.

5 In air preheaters of this character, the preheater is usually composed of a plurality of hollow plates which extend within the off-take for the waste products of combustion, the air being passed through the hollow plates, and the waste gases passing over the hollow plates. Sometimes the leading edges of these plates deteriorate because of the heat, this being so particularly where the amount of air being passed through the heat-
10 er is relatively small, as might be the case, for example, when the boiler is being operated for long periods of time at very low ratings.

The primary object of my invention is to overcome this difficulty.

15 20 The foregoing, together with such other objects as may hereinafter appear, or are incident to my invention, are realized by a construction which I have illustrated in a preferred form in the accompanying drawings.

25 Fig. 1 is a section through a stack of a pulverized-coal burning boiler installation showing the air preheater in side elevation, such air preheater embodying my improvements.

30 Fig. 2 is a fragmentary section taken on the line 2—2 of Fig. 1.

Referring now to the drawings, I have shown only those portions of the installation which are necessary to illustrate the character of my invention. The stack or other off-take is indicated at 7, and extending within the stack is the air preheater indicated, as a whole, by the reference character A. The air preheater consists of a plurality of hollow plates 8 through which the combustion air to be preheated is caused to flow in any preferred manner well understood in the art. The waste gases flow upwardly through the spaces between the plates. Obviously, the leading edges 8 of the plate will be subject to the greatest heat, and may well deteriorate for the reasons above pointed out.

To overcome this, I weld, or otherwise secure tubes 9 to the leading edges of the plates. These tubes are cooled, preferably by the circulation of water therethrough, although some other form of cooling medium may be employed. For this purpose, the tubes 9 are connected at their ends to the headers 10 and 11, respectively, which headers, in turn, have connections 12 and 13 for circulation. Where water is employed as the cooling medium, the leading edges and the tubes 9 would be inclined, as shown, and the connection 12 would function as a downcomer from the boiler, and the connection 13 as an upcomer to the boiler.

The advantages of my invention will be readily understood by those skilled in the art.

What I claim is:

1. In combination, a waste gas conduit, a plurality of air conduits extending in said gas conduit comprising a plurality of hollow plates spaced to provide gas passage therebetween, a manifold at each of two opposite sides of said gas conduit and outside thereof, a plurality of pipes connecting said conduits and located immediately in advance of the leading edges of said hollow plates, a cooling medium inlet to one of said manifolds and a cooling medium outlet from the other manifold.

2. In combination, a waste gas conduit, a plurality of air conduits extending in said gas conduit comprising a plurality of hollow plates spaced to provide gas passages therebetween, and cooling means for the leading edges of said air conduits comprising manifolds outside the gas conduit, a plurality of pipes connecting said manifolds and disposed immediately in advance of said edges, a cooling medium inlet for one of said manifolds, and a cooling medium outlet for the other manifold.

In testimony whereof I have hereunto signed my name.

CARL S. REED.
